(74) *Attorney, Agent, or Firm* — CANTOR COLBURN LLP

(57) **CLAIM**

The ornamental design for a sanitary napkin, as shown and described.

DESCRIPTION

FIG. 1 is a top plan view of a sanitary napkin showing my new design;

FIG. 2 is a bottom plan view thereof;

FIG. 3 is a top right perspective view thereof;

FIG. 4 is a left side elevation view thereof;

FIG. 5 is a right side elevation view thereof;

FIG. 6 is a front elevation view thereof; and,

FIG. 7 is a rear elevation view thereof.

The broken dash lines in the figures depict portions of the sanitary napkin that form no part of the claimed design. The gray coloration indicates a contrast appearance.

1 Claim, 5 Drawing Sheets
